UNITED STATES PATENT OFFICE.

PETER BROWN, OF CHICAGO, ILLINOIS, ASSIGNOR TO CHANNELL CHEMICAL COMPANY,
OF CHICAGO, ILLINOIS, A CORPORATION OF ILLINOIS.

MOP.

1,249,894.

Specification of Letters Patent. Patented Dec. 11, 1917.

Application filed January 3, 1915. Serial No. 86.

To all whom it may concern:

Be it known that I, PETER BROWN, a citizen of the United States, and a resident of the city of Chicago, in the county of Cook and State of Illinois, have invented certain new and useful Improvements in Mops; and I do hereby declare that the following is a full, clear, and exact description of the same, reference being had to the accompanying drawings, and to the numerals of reference marked thereon, which form a part of this specification.

A great many different types of oil mops have been devised with various objects in view, particularly that of permitting detachment of the mop fabric from the mop head for the purpose of cleaning the mop after continuous use. An objectionable feature to practically all previous constructions has been the necessity of handling the oily and dirty mop fabric in detaching the mop fabric from the mop head.

This invention relates to a mop head constructed for use upon a particular kind of mop fabric whereby means are provided for attaching and detaching the mop fabric from the mop head without necessitating handling of the mop fabric, particularly in detaching the same, it only being necessary 30 to actuate the mechanism by the fingers, the mop fabric immediately falling away from the mop head.

It is an object, therefore, of this invention to construct a device wherein expandible means are provided on the mop head for engaging a mop fabric thereto, and when released permitting the mop fabric to fall away therefrom without necessitating contact of the hands of the user with the oily 40 fabric of the mop.

It is also an object of this invention to construct a mop head provided with movable cam operated members adapted to engage the fabric of a mop upon the mop head and to release said fabric by release movement of a cam, said cam so shaped as to remain in a locked position with the members expanded to hold the mop fabric attached without auxiliary locking means.

50 It is also an object of this invention to construct a device wherein pivotally connected members are expandible away from one another upon a base plate and flanged

to engage the fabric of a mop, and equipped with mechanism for moving and maintaining the same in an expanded position.

It is furthermore an important object of this invention to construct a combined mop head and mop fabric, the mop fabric being a continuous closed loop attachable upon the 60 mop head by the expansion of flange members forming a part of said mop head, thus obviating the use of supplementary attaching means heretofore used threaded through the mop fabric.

It is finally an important object of this invention to construct a device simple in operation and acting efficiently to perform the purpose, permitting ready detachment of a mop fabric from the mop head without necessitating contact with the hands.

The invention (in a preferred form) is illustrated in the drawings and hereinafter more fully described.

In the drawings:

Figure 1 is a top plan view of a device embodying the principles of my invention.

Fig. 2 is a bottom plan view of the mop head, with the mop fabric removed.

Fig. 3 is a section taken on line 3—3 of Fig. 1.

Fig. 4 is a detail section taken on line 4—4 of Fig. 3.

Fig. 5 is a detail section taken on line 5—5 of Fig. 3.

Fig. 6 is a detail section taken on line 6—6 of Fig. 2.

Fig. 7 is a fragmentary detail section taken on line 7—7 of Fig. 1.

Fig. 8 is a fragmentary plan view illustrating a modified form of device.

As shown in the drawings:

The reference numeral 1, indicates a base plate, which is oval in shape and more or less pointed at one end, and pivoted on the upper surface thereof at the pointed end by a pin 2, are expandible engagement members for the mop fabric, each of which consists of a web 3, of double thickness, and an outwardly concave flange 4, projecting above and below said web and conforming substantially to the outline of the base plate 1. Short arc shaped slots 5, are formed in said plate 1, with the pivot 2, as a center, and engaged through each slot are flanged studs 105 or rivets 6, which are rigidly attached to the

webs 3, of the expandible members, thus guiding and limiting said members in their respective movements.

Integral ears 7, are struck upwardly from 5 said base plate 1, leaving apertures therein, and a handle socket member 8, provided with tongues 9, is pivoted to said ears by means of rivets 10, extending through said ears and tongues respectively. The under edge of 10 each of said tongues 9, is straight to limit the forward or upward swinging movement of the handle socket member 8, about the pivots 10, as clearly shown in Fig. 3, although the same may readily swing down 15 into a position substantially parallel to the base plate 1, if so desired. Pivoted flat upon the upper surface of the main base plate 1, by means of a pivot pin or rivet 11, is a double cam member 12, having upwardly 20 directed finger pieces 13 and 14, integral therewith. The two cam surfaces or edges of the cam members 12, are similar in shape, and near the outer end of said cam surfaces adjacent the finger pieces 13 and 14, respectively, the curvature is that of an arc of a 25 circle with a center coincident with the center of rotation of the cam 12. The respective webs 3, of the expandible members are provided with curved recesses 15, into 30 which the curved cam edges engage when the cam is rotated, to spread said respective members away from one another.

In the modification of my invention illustrated in Fig. 8, I have shown the cam edges 35 of a cam 16, as serrated, although the cam, as before, is mounted upon a pivot or rivet pin 17, and provided with finger actuating pieces 18 and 19, respectively. The web members 3, of the expandible members are 40 provided with serrated recesses 20, which contact with the serrations in the cam edges of the cam, so that when the cam is moved into an adjusted position it is prevented from slipping back or moving into any other 45 position, due to the engagement of said serrations with one another.

The operation is as follows:

When it is desired to attach the mop to the mop head, the handle socket member 8, 50 is swung downwardly about its pivots 10, into a substantially horizontal position, and the finger pieces 13 and 14, are actuated to move the cam into such position that said finger pieces are substantially in longitudinal alignment with the longitudinal axis of 55 the mop head. This permits the expandible members 3—4, to be moved inwardly toward one another about the pivot connection 2, and a mop fabric may then be attached to 60 the mop head. The mop fabric, which is indicated by the reference numeral 21, consists of a plurality of strands of fabric securely connected together at the hem 22, of the mop fabric, and the entire mop fabric 65 is a closed loop or continuous element. The

hem 22, of the mop fabric is placed around the outwardly concave flanges 4, of the expandible members of the mop head, or the mop head may be inserted into the mop fabric with said flanges engaging the hem thereof, and then the cam 12, is rotated by its finger pieces to expand the expandible members, thus forcing the flanges 4, of the respective members outwardly away from one another, causing the mop fabric to tighten upon the mop head with the hem engaged in the outwardly concave flanges. As the cam 12, is rotated into an extreme position, inasmuch as the curvature of the cam engaging edges thereof ends in an arc of a circle struck about the center of pivotal movement of the cam, a wedging effect is maintained which holds the expandible members apart, and the line of thrust on the cam is directly through the pivotal center thereof, so that there is no tendency for the same to accidentally rotate reversely and thus loosen the expandible members. After the expandible members have been so adjusted the socket member 8, is swung upwardly into the inclined position shown in Fig. 3, and this position of the same prevents the finger piece 14, of the cam from moving therewith and becoming loosened in the event that the cam should be accidentally struck.

In the modification of my invention illustrated in Fig. 8, I have shown the cam edges of the cam member 16, as well as the recesses in the flanges of the expandible members serrated, so that there is no possibility of jarring or knocking of the mop head causing a loosening of the cam which maintains the expandible members in expanded position.

I am aware that various details of construction may be varied through a wide range without departing from the principles of this invention, and I therefore do not purpose limiting the patent granted otherwise than necessitated by the prior art.

I claim as my invention:

1. In a device of the class described a base plate, expandible members pivoted thereon, and a double cam for actuating said expandible members into expanded position to clamp a mop fabric thereto.

2. In a device of the class described, the combination with a closed one piece mop fabric, of a mop head plate, a double cam pivoted thereon, and expandible means adapted to be engaged and actuated by said cam to engage the mop fabric to tighten the same on said means by expansion.

3. In a device of the class described, the combination with a mop head plate having arc shaped slots therein, of a unitary continuous closed mop fabric, expandible means on said mop head plate movable away from one another for releasably maintaining said mop fabric attached thereto, and studs rig-

idly secured to said expandible means projecting through the slot in said mop head plate for guiding and limiting the movement of said expandible means.

- 5 4. In a device of the class described a base plate, a plurality of expandible members pivoted thereon, a handle socket pivoted on said base plate, a cam pivoted on said base plate adapted to coact with said 10 expandible members to force the same apart, and means on said cam adapted to be engaged by said handle socket to prevent retractive movement of said cam.
5. In a device of the class described a mop 15 head plate, pivotal expandible means thereon adapted to be moved apart, a continuous closed mop fabric adapted to be engaged by said means to be retained thereon, and a cam the curvature of which is such that when 20 actuated said cam acts to separate said expandible members moving into a dead center

position to prevent accidental release movement thereof.

6. In a device of the class described the combination with a mop fabric, of a base 25 plate, expandible members pivoted thereon, a double cam pivoted on said base plate adapted to actuate said members, finger pieces integral with said cam for actuating the same to move said members apart to 30 clamp said mop fabric thereto, and means associated with said base plate and members to guide and limit the movement of said members.

In testimony whereof I have hereunto 35 subscribed my name in the presence of two subscribing witnesses.

PETER BROWN.
